UNITED STATES PATENT OFFICE.

ETHELRED ALFRED WILLSON, OF CROYDON, ENGLAND, ASSIGNOR TO CREED & COMPANY, LIMITED, OF CROYDON, ENGLAND.

TELEGRAPHIC RECEIVING APPARATUS.

Application filed July 19, 1920. Serial No. 397,229.

(GRANTED UNDER THE PROVISIONS OF THE ACT OF MARCH 3, 1921, 41 STAT. L., 1313.)

To all whom it may concern:

Be it known that I, ETHELRED ALFRED WILLSON, a subject of the King of Great Britain and Ireland, residing at Croydon, county of Surrey, England, have invented Improvements in or Connected with Telegraphic Receiving Apparatus (for which I have filed applications in Great Britain, Jan. 7, 1918, No. 379; in France, July 3, 1920, 10 518,814; in Canada, July 16, 1920, 244,188; in Denmark, Aug. 4, 1920, 2,458; in Sweden, June 28, 1920, 3,245; in Spain, July 2, 1920, 15 74,355; in Italy, July 8, 1920, 39,302; in Belgium, July 1, 1920, 230,710; in Holland, Aug. 9, 1920, 16,021), of which the following is a specification.

This invention relates to telegraphic receiving apparatus for perforating a tape in accordance with electric currents or impulses received over a line wire in automatic Wheatstone telegraphic systems and has for its primary object to provide improved apparatus which reproduces at the receiving end of a circuit an exact perforated tape replica of that which is run through the transmitting apparatus at the sending end of the circuit.

Another object of the invention is to provide receiving apparatus in which the use of costly and intricate air pressure plant and mechanism for operating the tape punches is obviated.

Still another object is to provide receiving apparatus capable of operating at a high speed, for instance at the rate of about 80-150 words per minute or even more.

It has heretofore been proposed to provide apparatus for producing a perforated tape in accordance with electric currents or impulses received over a line wire, said apparatus comprising two or three independently operating sets of mechanism controlled by two polarized relays one responsive to negative and the other to positive currents one set for operating a "dot" punch, a second for actuating a "dash" punch, and the third if such is provided, a "space" punch, and each set comprising a spindle section continuously rotated at a constant speed by an electric

motor, a spring-pressed spindle section aligning with the rotary spindle section and normally held stationary, a ratchet wheel or other toothed or notched clutch fitted between the two spindle sections and controlled by an electromagnet and a cam on the normally stationary spindle section and adapted to operate the respective punch through a plunger and key lever or through a pivoted striker.

The apparatus provided by the present invention embodies an improved construction combination arrangement and mode of operation of its parts, and comprises a single polarized relay provided with a member adapted to oscillate in response to the electric currents or impulses received over the line, a train of escapement devices and cams, one of which escapement devices directly and mechanically co-operates with the oscillatory member, and punch-operating devices which operate "dot" and "dash" punches of a receiving tape punching machine, the arrangement being such that each time the relay member oscillates to one side or the other all of the escapement devices and cams are momentarily released, and the cams mechanically driven a certain amount, successively and step by step, that is, in a train one after the other, the last cam directly actuating one of the punch-operating devices, and the small movements of the relay member being multiplied step by step through all of the escapement devices and cams to the larger and stronger movements necessary for operating the punches.

The invention will now be described with reference to the accompanying drawings, in which:—

Figure 1 is a side elevation, partly in section, of apparatus embodying the invention.

Figure 2 is a partly sectional plan of the apparatus with the platforms and the relay and intermediate release mechanisms removed;

Figures 3 and 4 are plans of the relay and intermediate release mechanisms, respectively;

Figure 5 is a front elevation on the line 5—5 of Figure 1;

Figure 6 is a front sectional elevation on the line 6—6 of Figure 1, and

5 Figure 7 is a front elevation on the line 7—7 of Figure 1,

In Figures 1, 3, 4 and 6 of the drawings the bell crank levers and their connecting links are shown in their intermediate positions 10 in order to enable their construction to be the better illustrated and understood upon reference to such drawings.

In the construction shown three, that is, relay, intermediate and punching, spindles 15 are mounted above one another on two platforms 6^a and a base plate 7^a and geared together by toothed wheels 8, 9 and 10, and each spindle is formed of two aligning sections 11—11^a, 12—12^a, 13—13^a, adapted to be 20 connected to one another by co-operating friction clutch discs 14—14^a, 15—15^a, and 16—16^a secured on their adjacent ends. One section 11, 12 and 13 of each spindle carries or is associated with an escapement herein- 25 after described and a cam 17, 18 and 19, and the other section 11^a, 12^a, and 13^a carries one of the gear wheels 8, 9, and 10, and has its free end supported in a bearing and engaged by an adjustable bearing screw 20, 20, 20. 30 Additional gear wheels 21, Fig. 2, form a train with the gear wheel 10, and one of the said additional wheels is connected to a shunt wound electric motor, of about 1th H. P. such as by a flexible coupling and a spindle 35 22, and other is connected to a shaft 23 which drives a stub shaft 24 through worm gearing 25, said stub shaft being provided with a fly wheel 26 and with a clutch device 27 or other means for driving the spindle 28 40 of the paper or other tape 29, said spindle forming part of a receiving tape punching mechanism such as of a "Creed punch block," and serving to feed the tape between the die-plates and past the punches of said 45 mechanism. By these means the spindle sections 11^a, 12^a and 13^a the clutch discs 14^a, 15^a and 16^a on these sections, and the tape operating mechanism 21 to 28 are 50 driven continuously at a predetermined constant speed from the electric motor, the speed being controlled by the adjustment of a rheostat connected in circuit with the field winding of the motor or by a suitable form of governor. Normally the other sections 55 11, 12 and 13 of the spindles and the clutch discs 14, 15, and 16, and the cams 17, 18 and 19 carried thereby are held against rotation by the escapement mechanisms until released in the manner hereinafter described. The 60 clutch discs 14, 15, and 16 on the normally stationary spindle sections 11, 12 and 13 are constantly pressed against leather or other rings 30, fixed to their co-acting clutch discs 14^a, 15^a and 16^a on the continuously rotating 65 spindle sections 11^a, 12^a and 13^a by means of

adjustable springs 31, 32 and 33, the springs 31 and 32 bearing against the ends of their respective spindle sections 11 and 12, whilst the spring 33 is attached to a pivoted lever 34, Figures 1 and 2 having a collar 35 which bears against the corresponding clutch disc 16 on the spindle section 13. The pressure of the springs 31, 32, and 33, is so adjusted that it is just sufficient to cause the respective spindle sections 11, 12 and 13, and the 70 cams, 17, 18 and 19, to turn smartly when said spindle sections are released, the power required to do the work allotted to each 75 complete spindle being taken automatically in the manner described hereinafter. The apparatus is electrically controlled direct from the line signals by an ordinary post office or other suitable polarized relay 36, Fig. 3 which latter has its electrical contacts replaced by a light steel tongue 37 adapted 80 to oscillate in response to the signal currents, between two adjustable stop screws not shown. The free end of the relay tongue 37 co-operates with two staggered radial arms 85 38 secured on the normally stationary section 90 11 of the upper spindle 11—11^a thus forming the first or relay escapement mechanism, and the adjustment, sizes and shapes of the tongue and arms in relation to one another 95 are such that said arms can make only one half revolution upon each movement or beat of the tongue to the right or left.

The operation of the parts of the apparatus so far described and of the other parts of same hereinafter referred to, will now be 100 described, it being first pointed out however that two punches are involved in the production of perforations representing a dot as well as a dash, the punches being staggered in the direction of travel of the 105 tape in suchwise that in the case of a dot there is a dwell after actuation of one punch just sufficient to cause the second punch to produce a perforation at the same position in the length of the tape, the two perforations being at opposite sides of the customary centre line of feed perforations. The 110 production of perforations representing a dash is effected by the first punch in the same way as for a dot but the dwell in this case is increased so that the second punch produces a companion perforation which is not in the same position in the length of the 115 tape but coincides with the next feed perforation. It will thus be understood that as the complete operation of thrusting and releasing the punches occupies only about the 300th part of a second, the time during 120 which the feed wheel and tape are arrested is practically negligible and the difference 125 between dots and dashes in the tape depends entirely therefore upon the time interval between successive spacing and marking contacts during which the tape is allowed to 130 run on. Even between the marking and

spacing currents for a dot, there is an appreciable interval during which the slip has travelled a little. The right-hand punch and the corresponding corrector wheel are given a lead so that although the spacing punch is actuated later, the spacing perforation appears opposite the same centre hole as the marking perforation. The operation is thus as follows:—A movement of the relay tongue 37 to one side under the influence of a received signal current causes it to release one of the first escapement arms 38 on the upper spindle section 11, so that the latter turns through half a revolution until the other arm contacts with and is stopped by the tongue. The cam 17, Figures 1, 3 and 6, on the spindle section 11 engages and presses back an arm of one of two opposed bell-crank levers 39, 39 pivoted on a stationary support 40 secured on the upper platform 6, the other arms of which levers are connected by a link 41 and by a pin and hole joint 42 to the upper end of a vertical lever 43 pivoted at 44, Figures 1 and 6 the lower end of said lever or rod being forked and engaged with a stud 45 on a plate 46 forming part of the second or intermediate escapement mechanism and slidably mounted in the recessed rear face of a stationary support 47. The movement of the bell crank lever 39 by the cam 17 pushes the plate 46 to one side, and this action is caused to be smart and decisive by the medium of a roller 48 carried by a spring 49 operating with a projection 50 carried by the pivot pin of the vertical lever 43. Thus the lever 43 and the plate 46 operated thereby cannot come to rest at any intermediate position but once the projection 50 passes the neutral line said lever and plate must, through the action of the spring roller 48, jump to one side or the other according to the operation and position of the cam 17.

Two catch plungers 51, 51 are slidably and longitudinally mounted in the support 47 and are connected to lugs 52 formed on plates 53, Fig. 4 secured, adjustably if desired, to the plate 46, and said lugs slide in slots formed in the said support. The movement of the second escapement plate 46 causes one of the catches 51 to release an arm 54 secured to the spindle section 12 and engaging said catch so that the said spindle section is allowed to rotate through half a revolution until said arm contacts with and is stopped by the other catch 51. The cam 18, Figs. 1 and 4 on the spindle section 12 engages and presses back an arm of one of two opposed bell-crank levers 55 pivoted on the stationary lower platform 6^a, the other arms of which levers are connected by a link 57, Figs. 1, 4 and 5, carrying a pointed projection 58 which passes through a slot 59 formed in a depending lever 60 pivoted at 61 and having its lower end forked to en-

gage a stud 62 on a plate 63 serving as part of the third or punching escapement mechanism and slidably mounted in the recessed rear face of a stationary support 64. Two catch plungers 65, 65 are slidably and longitudinally mounted in the support 64 and are connected to lugs 66 formed on discs 67 secured, adjustably if desired, to the plate 63, and said lugs slide in slots formed in the said support. The movement of the bell crank lever 55 by the cam 18 swings the link 57, depending lever 60 and plate 63 to one side, and the swinging action is rendered sudden by any known or suitable device such as by means of a roller 68 carried by a spring 69 and co-operating with the pointed end of the projection 58 on said link in a manner and for a purpose similar to those of the spring roller 48 and projection 50 previously described.

The swinging aside of the third escapement plate 63 caused one of the catches 65 to release an arm 70 secured on the lower or punching spindle section 13, so that the latter is allowed to revolve through half a revolution until said arm contacts with and is stopped by the other catch of the plate. The cam 19 on the spindle section 13 engages with one of a pair of rollers 71, Figs. 2 and 7 carried by two hinged spring-returning striking plates 72, thus pressing the respective plate forward. These striking plates 72 are adapted to operate the "dot" and "dash" punches 73 and the corrector-rods 74 of the receiving tape punching mechanism indicated generally by dot and dash lines 75.

When the relay tongue 37 moves to the other side under the influence of a succeeding signal current the escapement and cam mechanisms repeat the operations above described with the exception that the movements of the second and third escapement plates 46 and 63 will be in reverse directions and the third cam 19 will actuate the second striking plate 72 instead of the one previously operated. These movements in opposite directions of the escapement plates 46 and 63 and the alternate operations of the two striking plates 72 are ensured as will be appreciated, by the co-operation of the two arms 38 of the first escapement with the relay tongue 37 by the pairs of opposed bell crank levers 39 and 55 co-operating with the first and second cams 17 and 18 and by the consequential rotation of the three spindle sections 11, 12 and 13 each through half a revolution at a time and in turn. Thus it will be understood that the small and timed side movements of the relay tongue 37 in alternate directions, under the influence of positive and negative or strong and weak currents are exactly reproduced in steps but to a multiplied degree by the movements imparted to the two striking or punch-operating plates 72.

The three cams 17, 18 and 19, are so shaped that the greater the resistance they have to overcome the harder are the discs 14, 15 and 16 thrust against their companion rotating 5 discs 14^a, 15^a and 16^a thus each spindle section 11, 12 and 13, automatically obtains the necessary power to do the work allotted to it.

The arms of the opposed bell crank levers 39 and 55 which engage with the cams 17 10 and 18 have rollers 76 and 77 mounted on them to reduce friction. For the same reason the free end of the tongue 37 moves on rollers not shewn.

The striking plates 72 are thrust forward 15 by the cam 19 and returned by the springs 78 against the adjustable stops 79 so quickly that the time that the tape is held and punched is so short as to be negligible. The action of the receiving tape punching mechanism known as the "Creed punch-block" is 20 well known and need not be detailed here. It will be sufficient to say that the action and effect produced by the striking plates 72 is the same as that produced by the punch hammers of the "Creed receiver" the instrument 25 with which the "Creed punch block" is normally used. For an understanding of the Creed punch block and receiver reference may be had to U. S. Patent No. 887,313.

30 The cam 19 is fitted on the back with a circumferentially adjustable disc 80 upon which are two projections or cams 81 diametrically opposite to one another. These two projections 81 are so adjusted by turning the disc 80 that they contact with the adjustable screws 82 just before the arm 70 strikes and is stopped by one of the catches 65 which action momentarily relieves the pressure between the two discs 16 and 16^a. 35

40 Thus the arm 70 strikes the catches 65 while the power is temporarily removed from the spindle section 13 which action will tend to materially reduce the power required to operate the instrument as well as to minimize the wear and tear at this point.

45 The springs 31 and 69 are each adjusted by means of two set screws passing through slots therein and disposed one on each side of the block 83 secured thereto and formed with opposed inclined faces, the spring 32 50 is carried by a pivot pin upon which is secured an arm 84 against which presses an adjustable set screw 85 and the rear end of the spring 33 is secured to a longitudinally 55 moveable screw-threaded bolt 86 which is adjusted by two nuts 87. The plate 46 moves between two adjustable stop screws 88 and the lever 60 between two similar screws 89.

60 If desired two instead of three sets of escapement and cam mechanisms, or more than three may be provided.

What I claim is:

65 1. A telegraphic tape perforator of the kind herein referred to, comprising tape feeding mechanism, punches for forming

signal holes in tape fed by said mechanism, punch operating means, a single polarized relay having a member adapted to move alternately in opposite directions in response to positive and negative electric impulses 70 received over a telegraph line associated with said relay, a series of normally stationary rotary members, actuating means on each rotary member, driving means designed constantly to rotate when the perforator is 75 in use, a closed friction clutch between each rotary member and said driving means, holding means associated with each rotary member for normally holding the same stationary, against the action of its clutch, the holding means associated with the first rotary member in the series being controlled by the movable member of the relay, the holding means associated with the second rotary member in the series being controlled 80 by the actuating means on the first rotary member and so on, the actuating means on the last rotary member being adapted when such member is released, to actuate the punch operating means, and the several 85 clutches being of increasing power from that associated with the first rotary member to that associated with the last rotary member, substantially as described.

2. A telegraphic tape perforator of the 90 kind herein referred to, comprising tape feeding mechanism, two punches for forming signal holes in tape fed by said mechanism, means for actuating said punches in alternate order, a series of rotary members, 95 a series of cams fixed to the respective rotary members, driving means designed continuously to rotate, a series of closed friction clutches between said driving means and rotary members, a single polarized relay 100 having a member adapted to be moved alternately in opposite directions in response to positive and negative impulses received over a telegraph line, and a series of escapement devices associated with the respective 105 rotary members and each adapted normally to hold its respective shaft stationary, the first escapement device in the series being controlled by the said movable member of the relay and the next escapement device in 110 the series being controlled by the cam on the preceding rotary member of the series, the first escapement being arranged to be released by the relay member when moved in either direction and its corresponding rotary 115 member left free to be rotated by its corresponding clutch device and its cam device then caused to release the escapement device of the next rotary cam carrying member in the series and permit such member to be rotated by its clutch device and so on, the cam device on the last rotary member being 120 arranged, when rotated, to operate the punch actuating means.

3. A telegraphic tape perforator of the 125 130

- kind herein referred to, comprising tape feeding mechanism, two punches for forming signal holes in tape fed by said mechanism, actuating means for said punches, a 5 single polarized relay having a member adapted to be moved alternately in opposite direction by positive and negative in said relay in response to positive and negative impulses in a telegraph line associated with 10 said relay, driving means adapted to be continuously rotated, a series of driving spindles arranged to be continuously rotated from said driving means, a series of normally stationary driven spindles arranged 15 co-axially with the respective driving spindles, a cam on each driven spindle, a closed friction clutch between each pair of driving and driven spindles, escapement mechanism associated with each driven spindle and normally 20 holding said spindle stationary against the action of its clutch, the escapement mechanism associated with the first driven spindle being controlled by the relay member and being released at each movement 25 of said member, and the escapement mechanism associated with each succeeding stationary spindle being controlled and actuated by the cam on the preceding driven spindle when this spindle is released by its 30 escapement and driven by its clutch, the cam device on the last stationary spindle being adapted when such spindle is released by its escapement and driven by its clutch to operate the punch actuating mechanism, and the 35 several cams being of increasing power from the first to the last in the series, substantially as described.
4. In a telegraphic tape perforator of the kind herein referred to, the combination 40 with tape feeding mechanism, punches for forming signal holes in a tape fed by said mechanism, actuating means for said punches, and a single polarized relay having a member adapted to be moved alternately 45 in opposite directions in response to positive and negative impulses received over a telegraph line associated with said relay, of series of driving spindles, a series of companion normally stationary driven spindles, 50 each of the latter spindles being co-axial with a driving spindle, a closed friction clutch between the adjacent ends of each pair of driving and driven spindles and adapted to slip when the driven spindle is 55 stationary, a cam fixed on each driven spindle, an escapement device associated with each driven spindle, that associated with the first driven spindle of the series thereof comprising two diametrically arranged arms fixed on the said first driven 60 spindle and co-operating with the movable member of said relay so that said driven spindle can be rotated through half a revolution by its clutch each time the relay 65 member moves from one position to another,
- means arranged between the cam on each driven spindle and the escapement device associated with the next driven spindle in the series of driven spindles and adapted, when the first driven spindle is released, to 70 be actuated by the cam thereon and to actuate the escapement to release the said next driven spindle, the successive clutches being of successively increasing power from that associated with the driven shaft first released by the action of the relay and the cam on the last shaft of the series being adapted, when its driven shaft is momentarily released by its escapement mechanism and driven by its clutch to operate the 75 punch actuating means.
5. In a telegraphic tape perforator of the kind herein referred to, the combination with tape feeding mechanism, tape punching mechanism and a single polarized relay 80 having a member adapted to move alternately in opposite directions in response to positive and negative impulses received over a telegraph line associated with said relay, of a number of pairs of coaxial driving and driven spindles arranged parallel to one another, means for continuously rotating the driving spindles, a closed friction clutch between each pair of driving and driven spindles, a cam on each cam shaft, escapement 85 means for normally holding each driven spindle stationary against the action of its clutch, the escapement means for the first driven spindle of the series being controlled by the movable relay member and that for 90 each succeeding cam shaft being controlled from the cam on the preceding driven spindle, the several escapement means acting in succession to release the respective driven spindles and allow them to be rotated in 95 succession through half a revolution each time the movable relay member moves from one position to another, the clutches being of increasing power from the first driven spindle to the last and the cam on the last driven spindle, when this spindle is released, acting to operate the tape punching mechanism.
6. In a telegraphic tape perforator of the kind herein referred to, the combination 100 with tape feeding mechanism, tape punching mechanism and a single polarized relay having a member adapted to move alternately in opposite directions in response to positive and negative impulses received over 105 a telegraph line associated with the relay, of a plurality of pairs of driving and driven members, a closed friction clutch between the driving and driven members of each pair thereof, an escapement on the first 110 driven member adapted to be momentarily released at each movement of the said movable member of the relay and permit said spindle to be driven by its clutch, means 115 arranged between the said several driven 120 members.
7. In a telegraphic tape perforator of the kind herein referred to, the combination 125 with tape feeding mechanism, tape punching mechanism and a single polarized relay having a member adapted to move alternately in opposite directions in response to positive and negative impulses received over a telegraph line associated with the relay, of a plurality of pairs of driving and driven members, a closed friction clutch between the driving and driven members of each pair thereof, an escapement on the first driven member adapted to be momentarily released at each movement of the said movable member of the relay and permit said spindle to be driven by its clutch, means arranged between the said several driven 130 members.

members, adapted, when the first driven member is released, to release succeeding driven members in succession and permit them to be rotated by their clutches and means on the last driven member adapted, when this member is released and rotated, to actuate the tape punching mechanism, the

several clutches being of increasing power from that of the first driven member to the last one.

10

Signed at London, England, this 22nd day of June, 1920.

ETHELRED ALFRED WILLSON.
